UNITED STATES PATENT OFFICE

163,889

COMBINED ASH TRAY AND HOLDER FOR COINS, GAME CHIPS, CIGARETTES, AND MATCHESJerry Meyer, New York, Siegbert Strauss, Bell-port, and Sender Stutzel, New York, N. Y.

Application October 24, 1950, Serial No. 12,938

Term of patent 14 years

(Cl. D85—2)

To all whom it may concern:

Be it known that we, Jerry Meyer, a citizen of the United States, Siegbert Strauss, a citizen of the United States, and Sender Stutzel, who is stateless, residing at New York, Bellport, and New York, State of New York, respectively, have invented a new, original, and ornamental Design for Combined Ash Tray and Holder for Coins, Game Chips, Cigarettes, and Matches, of which the following is a specification, reference being had to the accompanying drawing, forming part hereof.

Fig. 1 is a front perspective view of combined ash tray and holder for coins, game chips, cigarettes, and matches, showing our new design; and

Fig. 2 is a rear perspective view thereof.

We claim:

The ornamental design for a combined ash tray and holder for coins, game chips, cigarettes, and matches, as shown.

JERRY MEYER.

SIEGBERT STRAUSS.

SENDER STUTZEL.
